UNITED STATES PATENT OFFICE.

HENRY M. WEAVER, OF MANSFIELD, OHIO, ASSIGNOR TO THE BARR CASH AND PACKAGE CARRIER COMPANY, OF SAME PLACE.

BASKET BAIL OR FORK.

SPECIFICATION forming part of Letters Patent No. 570,438, dated October 27, 1896.

Application filed June 2, 1896. Serial No. 594,025. (No model.)

To all whom it may concern:

Be it known that I, HENRY M. WEAVER, a resident of Mansfield, in the county of Rich-
5 land and State of Ohio, have invented certain
new and useful Improvements in Basket Bails
or Forks; and I do hereby declare the follow-
ing to be a full, clear, and exact description
of the invention, such as will enable others
skilled in the art to which it appertains to
10 make and use the same.

My invention relates to an improvement in
basket bails and forks for cash and pack-
age carriers, the object being to provide
against the accidental dropping of the basket
15 from the carrier, it being an improvement on
the Otto Konigsow patent, No. 513,512,
granted January 30, 1894, and consisting in
certain novel features of construction and
combinations of parts which will be herein-
20 after described and pointed out in the claims.

In the accompanying drawings, Figures 1,
2, 3, and 4 are views showing the different
positions assumed by the toggle or tumbler.
Fig. 5 is a view of the bail; and Fig. 6 is a
25 horizontal sectional view through the staple-
bolts.

A represents the bail of the basket, it being
provided with the restricted central portion
1, and pivoted to it is the toggle or tumbler 2,
30 as in the Konigsow construction. The latches
3 3, however, are different, and in this par-
ticular portion of the invention reside my im-
provements. Instead of these latches reach-
35 ing into the restricted center of the bail and
engaging and locking the tumbler or toggle,
they are pivotally connected at their inner
ends to the staple-bolts 4 4, which latter slide
loosely in and out and are guided in their
40 movements by the holes 5 5 in the guards or
flanges 6 6, springs 7 7 in the bail back of
these latches normally holding them down-
ward and the staple-bolts inward over the
narrow or restricted center 1.

B is the depending fork which receives the
45 bail A and to which the latter is locked. This
fork has precisely the same internal construc-
tion as the Konigsow fork, that is to say, it
has the three projections 18, 19, and 20
adapted to turn, control, and support the
50 toggle or tumbler 2, whereby to effect a lock-
ing of the bail within the fork, and, in addi-

tion to these features it possesses in common
with the Konigsow device, it has the four
elongated vertical slots 22 22, which receive
the staple-bolts 4 4 as they are released to pre-
55 vent the descent of the bail from the fork.

The invention is operated in the following
manner: The usual lifting-hooks, taking un-
der the bail, elevate the latches 3 3 when the
hook is raised, removing the bolts 4 4 from
the path of the hooks. The point 23 of the
tumbler or toggle engages the under side of
the projection 20, as in Fig. 1, and as the bail
is raised still higher the tumbler or toggle
swings to the position shown in Fig. 2, the
65 notch 24 in its heavier end receiving the pro-
jection 19. The operator now lets go or re-
leases the hook and the bail drops, the tum-
bler or toggle assuming the position shown in
Fig. 3 and the staple-bolts 4 4 entering the
70 slots 22 22. Thus while the toggle or tumbler
itself ordinarily locks the bail in the fork,
yet to doubly guard against the danger of
accidents, the bolts by shooting forward into
the slots absolutely prevent accidental drop-
75 ping or displacement of the basket. To re-
lease the bail from the fork, another upward
pull is given the bail. This causes the tum-
bler or toggle to swing by its own gravity into
the position shown in Fig. 4, and the latches 80
3 3, resting with the weight of the basket
upon the hook, cause the staple-hooks to
withdraw from the slots, causing a release of
the basket from the fork. So it will be seen
that the accidental dropping of the basket is
85 absolutely precluded, and while there was a
possibility of the tumbler or toggle in the
Konigsow device failing to act promptly, in
this device such failure is beyond the realm
of possibility, and it is evident that the toggle
90 or tumbler might be dispensed with alto-
gether, as well as the projections inside the
fork, and that other slight changes might be
made without departing from the spirit and
scope of my invention. Hence I do not wish
95 to limit myself to the exact construction
herein set forth, but,

Having fully described my invention, what
I claim as new, and desire to secure by Let-
ters Patent, is—

1. The combination with a fork having
openings or slots therein, of a bail, slide-bolts

therein, and latches loosely connected with the bolts and in position to be operated by the hook in raising the basket, substantially as set forth.

5 2. The combination with a bail, a pair of staple-bolts, and pivoted latches for controlling said bolts, of a fork having openings to receive said bolts, substantially as set forth.

3. The combination with a bail having 10 guards or flanges with holes therein, staple-bolts arranged to slide in said holes and spring-actuated pivoted latches loosely connected with the bolts, of a fork having openings therein in its sides to receive these bolts, 15 substantially as set forth.

4. The combination with a fork having projections therein and elongated slots in the sides, of a bail, a pivoted toggle or tumbler which engages and is controlled by the projections, slide-bolts and spring-actuated 20 latches connected with the bolts for sliding them, substantially as set forth.

In testimony whereof I have signed this specification in the presence of two subscribing witnesses.

HENRY M. WEAVER.
